UNITED STATES PATENT OFFICE.

LESTER E. SPRAY, OF WILKINSBURG, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY SIGNALING SYSTEM.

Application filed May 4, 1925. Serial No. 27,740.

To all whom it may concern:

Be it known that I, LESTER E. SPRAY, a citizen of the United States, residing at Wilkinsburg, in the county of Allegheny and 5 State of Pennsylvania, have invented certain new and useful Improvements in Railway Signaling Systems, of which the following is a specification.

My invention relates to railway signaling 10 systems, and particularly to systems of the type wherein a stop indication and two caution indications are given in the rear of a train.

I will describe one form of system embodying my invention, and will then point out the novel features thereof in claims.

The accompanying drawings, when placed end to end, are a diagrammatic view showing one form of signaling system embodying my invention.

Referring to the drawings, the reference characters 1 and 1^a, designate the track rails of a railway along which traffic normally moves in the direction indicated by the arrows. These rails are divided by insulated joints 35 to form a plurality of track sections of which three complete sections A—B, B—C and C—D, are shown in the drawings.

Located adjacent the entrance end of each section is a signal which is designated by the reference character S, with an exponent corresponding to the location. Each of these signals in the form here shown is of the one-arm three-position semaphore type, arranged to indicate "proceed," "caution" and "stop," according as the arm is in the vertical, the inclined, or the horizontal position.

Each track section is provided with a 40 track circuit comprising a source of current connected across the rails at the exit end of the section, and a track relay connected across the rails at the entrance end of the section. As here shown, the source of current for each track circuit is a transformer designated by the reference character J, with an exponent corresponding to the location. The secondary 7 of each transformer is connected across the track rails through a reactance 8 in the manner hereinafter explained. The primary 6 of each track transformer J is connected with the secondary 5 of a line transformer designated by the reference character H, with an exponent corre-

sponding to the location. The primary 4 of each transformer H is connected with a transmission line G which is constantly supplied with alternating signaling current by a generator F. The track relay for each section is designated by the reference character T, with an exponent corresponding to the location, and comprises a track winding 2 constantly connected across the rails of the section, and a local winding 3 constantly supplied with alternating current from the secondary 5 of the adjacent line transformer H. Each track relay T is responsive, therefore, to reversals of the relative polarity of the current in the track circuit of the associated section.

Each alternate section, such as section A—B and section C—D, is provided with an auxiliary relay designated by the reference character E, with an exponent corresponding to the location, and each of these auxiliary relays E is controlled by the signal for the second section in advance. Referring specifically to relay E^D, the circuit for this relay passes from the secondary 5 of line transformer H^B, through wire 18, circuit controller 19^B operated by signal S^B, wire 20, winding of relay E^D, and wire 21 to the secondary 5 of transformer H^B. Circuit controller 19^B is closed when signal S^B indicates proceed or caution, but is open when 85 this signal indicates stop, and, consequently, relay E^D is energized only when signal S^B indicates proceed or caution.

Each signal S operates a pole-changer designated by the reference character P, with an exponent corresponding to the location, and each pole-changer is included in the track circuit for the section next in the rear. The selective polarity of the track circuit current for each of the alternate sections A—B and 95 C—D is controlled solely by the pole-changer P associated with the track circuit for such section. Referring, for example, to section C—D, when signal S^C indicates proceed or caution, pole-changer P^C is in the normal 100 position wherein current of normal relative polarity is supplied to the rails of section C—D, with the result that the track relay T^D is energized in normal direction wherein the contacts of this relay are swung to 105 their left-hand positions. When signal S^C indicates stop, however, pole-changer P^C is in the reverse position, so that track relay

T^D is energized in the reverse direction wherein the contacts of this relay are swung to their right-hand positions.

The relative polarity of the track circuit current in each intermediate section is determined by the associated pole-changer P^B and also by the contacts 25 and 32 of the track relay for the section next in advance. Referring specifically to section 5 B-C, when signal S^B indicates proceed and track relay T^B is energized in the normal direction, that is, when these parts are in the positions shown in the drawing, track circuit current for section B-C flows from 10 the secondary 7 of track transformer J^B , through reactance 8, right-hand arm 22 of pole-changer P^B , wire 23 and 24, normal contact 25-25^a of track relay T^B , wires 26 and 15 27, to track rail 1^a, and from track rail 1, through wires 28 and 29, left-hand arm 30 of pole-changer P^B , wire 34, contact 32^a-32 of relay T^B , and wire 33 to the secondary 7 of transformer J^B . The current which is then supplied to the rails of section B-C 20 is of normal relative polarity, so that track relay T^C is energized in the normal direction and the contacts of this relay are swung to their left-hand positions, as shown in the drawing. I will now assume that track relay T^B is de-energized, and that signal S^B indicates stop, this being the condition assumed by these parts when section A-B is occupied by a train. Pole-changer P^B will 25 then be reversed and track circuit current for section B-C will flow from the secondary 7 of transformer J^B through reactance 8, right-hand arm 22 of the pole-changer P^B , wires 29 and 28 to track rail 1 of section B-C, and from track rail 1^a 30 of this section, through wires 27 and 36, back contact 32^b-32 of relay T^B , and wire 33 to secondary 7 of transformer J^B . The track circuit current which is then supplied to section B-C is of reverse relative polarity, 35 so that track relay T^C will be energized in the reverse direction, with the result that contacts of this relay will be swung to their right-hand positions. I will now assume that track relay T^B is energized in the reverse 40 direction and that signal S^B indicates caution. Track circuit current for section B-C will then flow from the secondary 7 of transformer J^B , through reactance 8, right-hand arm 22 of pole-changer P^B , wires 23 and 24, 45 reverse contact 25-25^b, wires 31 and 28, to track rail 1, and from track rail 1^a, through wires 27 and 36, reverse contact 32^b-32 of track relay T^B , and wire 33 to secondary 7 of transformer J^B . The track circuit current which is then supplied to section B-C 50 is still of reverse relative polarity, so that track relay T^C is still energized in the reverse direction. I will now assume that track relay T^B is energized in the normal 55 direction, but that signal S^B continues to

indicate caution. Pole-changer P^B is then in the normal position, so that current of normal relative polarity is supplied to the rails of section B-C through the same path as when signal S^B is in the proceed position 70 and relay T^B is energized in normal direction.

The signal S for each alternate track section, such as A-B and C-D, is controlled jointly by the associated track relay T and the associated auxiliary relay E . Referring particularly to signal S^B , this signal is provided with a caution indication circuit which is closed whenever track relay T^B is energized in the normal or the reverse direction, 75 this circuit being from secondary 5 of line transformer H^B , through wire 38, normal contact 9-9^a or reverse contact 9-9^b of relay T^B , wire 10, operating mechanism of signal S^B , wire 11, normal contact 12^a-12 80 or reverse contact 12^b-12 of relay T^B , and wire 37 to the secondary 5 of transformer H^B . Signal S^B is provided with a proceed indication circuit which is energized whenever track relay T^B is energized in the normal direction and the auxiliary relay E^B is energized; this circuit passes from the secondary 5 of transformer H^B , through wire 38, normal contact 9-9^a of track relay T^B , 85 normal contact 14-14^a of the same relay, wire 15, contact 16 of relay E^B , wire 17, operating mechanism of signal S^B , wire 11, normal contact 12^a-12 of relay T^B , and wire 37 to the secondary 5 of transformer H^B . 90

Signal S^D for the alternate section C-D 100 is provided with circuits which are similar to those for signal S^B .

The signal for each intermediate section is controlled only by the track relay for its section. Referring, for example, to signal S^C , this signal is provided with a caution indication circuit which is closed when track relay T^C is energized in reverse direction, this circuit being from secondary 5 of transformer H^C , through wire 38, reverse 105 contact 9-9^b of relay T^C , wire 10, operating mechanism of signal S^C , wire 11, reverse contact 12^b-12 of relay T^C , and wire 37 to secondary 5 of transformer H^C . Signal S^C 110 is also provided with a proceed indication circuit which is closed when track relay T^C is energized in the normal direction, this circuit being from secondary 5 of transformer H^C , through wire 38, normal contact 9-9^a of relay T^C , wire 13, operating 115 mechanism of signal S^C , wire 11, normal contact 12^a-12 of relay T^C , and wire 37 to the secondary 5 of transformer H^C . 120

The circuits for signal S^A are similar to the circuits just traced for signal S^C . 125 The operation of the system is as follows: When a train moving toward the left, that is, in the direction indicated by the arrow, enters section C-D, it de-energizes track relay T^D so that signal S^D moves to the stop 130

position. As the train enters section B—C, it de-energizes track relay T^c , so that signal S^c moves to the stop position, but as the rear end of the train leaves section C—D 5 track relay T^d becomes energized in the reverse direction because pole-changer P^c is now in the reverse position due to signal S^c being in the stop position. The caution indication circuit for signal S^d is therefore 10 closed at contacts 9 and 12 to relay T^d , so that this signal moves to the caution position. As the train enters section A—B it de-energizes track relay T^b , so that signal S^b moves to the stop position. As soon 15 as the rear end of the train leaves section B—C, track relay T^c becomes energized in the reverse direction, because pole-changer P^b is in the reverse position and track relay T^b is de-energized. Signal S^c therefore 20 moves to the caution position, with the result that pole-changer P^c returns to its normal position, and so track circuit current of normal relative polarity is supplied to section C—D. Track relay T^d therefore 25 becomes energized in the normal direction, but auxiliary relay E^d is de-energized because signal S^b is in the stop position. It follows that signal S^d remains in the caution position while the train occupies section A—B. 30 As the train enters the section to the left of point A, it de-energizes track relay T^a so that signal S^a moves to the stop position. As the rear end of the train leaves section A—B, current of reverse relative 35 polarity is supplied to the rails of this section because pole-changer P^a is reversed, and so track relay T^b becomes energized in the reverse direction. This causes signal S^b to move to the caution position, thereby 40 closing circuit controller 19^a. Auxiliary relay E^b then becomes energized, so that signal S^b moves to the proceed position. Signal S^b now being in the caution position, pole-changer P^b is in its normal position, 45 but track relay T^b is energized in the reverse direction, so that the current supplied to the rails of section B—C is still of reverse relative polarity. Track relay T^c continues to be energized in the reverse direction, so that signal S^c continues to indicate 50 caution. As the train passes out of the section to the left of point A, signal S^a will return to the caution position so that pole-changer P^a will be restored to its normal 55 position, thereby supplying track circuit current of normal relative polarity to section A—B. Track relay T^b will then become energized in normal direction and signal S^b being in the caution position pole-changer P^b will be in its normal position with the result that the track circuit current supplied to the rails of section B—C will be of 60 normal relative polarity. Track relay T^c will then be energized in the normal direction and signal S^c will indicate proceed. 65

Signal S^b will return to the proceed position when the train passes the third signal in advance of point B, and signal S^a will likewise return to the proceed position when the train passes the third signal in advance 70 of point A.

One feature of my invention is the fact that an auxiliary relay E is required at only every other signal location, so that I require only half as many auxiliary relays 75 as have heretofore been required for double-caution indication signaling.

Although I have herein shown and described only one form of signaling system embodying my invention, it is understood 80 that various changes and modifications may be made therein within the scope of the appended claims without departing from the spirit and scope of my invention.

Having thus described my invention, what 85 I claim is:

1. In combination, a railway track divided into successive sections, a track circuit for each section including a source of current and a track relay responsive to reversals of the relative polarity of the track circuit current, an auxiliary relay for each alternate section, a signal for each section, means for controlling the signal for each of 90 said alternate sections by the track relay and the auxiliary relay for the associated section, means for controlling the signal for each intermediate section by the track relay for the associated section, a pole-changer associated with each signal and included in 95 the track circuit for the section next in the rear, contacts of the track relay for each of said alternate sections included in the track circuit for the section in the rear for causing the track circuit current in such 100 section in the rear to be of reverse relative polarity when such track relay is energized in reverse direction and also when it is de-energized, and means for controlling each 105 said auxiliary relay by the signal for the second section in advance.

2. In combination, a railway track divided into successive sections, a track relay for each section responsive to reversals of relative polarity of the track circuit current in the rails of the section, a signal for each section, means controlled by the signal and the track relay of each alternate section for supplying the section next in the rear with 115 track circuit current of normal relative polarity when the signal indicates proceed or caution and the track relay is energized in normal direction and with track circuit current of reverse relative polarity under all other conditions, means controlled by the 120 signal for each intermediate section for supplying the section next in the rear with track circuit current of normal relative polarity when the signal indicates proceed or caution and of reverse relative polarity when 125 130

the signal indicates stop, an auxiliary relay for each of said alternate sections energized when the signal for the second section in advance indicates proceed or caution but not when it indicates stop, means for causing the signal for each of said alternate sections to indicate proceed when the associated track relay is energized in normal direction and the associated auxiliary relay is energized but to indicate caution when the associated track relay is energized in normal or reverse direction and the associated auxiliary relay is de-energized, and means for causing the signal for each intermediate section to indicate proceed or caution according as the associated track relay is energized in normal or reverse direction.

3. In combination, a railway track divided into successive sections, a track circuit for each section including a source of current and a track relay responsive to reversals of the relative polarity of the track circuit current, a signal for each section, means for each alternate section for controlling the relative polarity of the track circuit current in the section by only the signal for the section in advance, means for each intermediate section for controlling the relative polarity of the track circuit current in the section by the signal and also

the track relay for the section next in advance, an auxiliary relay for each of said alternate sections controlled by the signal for the second section in advance, means for controlling the signal for each of said alternate sections by the associated track relay and auxiliary relay, and means for controlling the signal for each intermediate section by the associated track relay.

4. In combination, a railway track divided into sections, a track relay for each section responsive to reversals of the relative polarity of the track circuit current in the rails of the section, a signal for each section, means controlled jointly by the signal and the track relay of each alternate section for supplying track circuit current of normal or reverse relative polarity to the section next in the rear, means controlled by the signal only of each intermediate section for supplying track circuit current of normal or reverse relative polarity to the section next in the rear, means for controlling the signal for each of said alternate sections by the associated track relay and by the signal for the second section in advance, and means for controlling the signal for each of said intermediate sections by only the associated track relay.

In testimony whereof I affix my signature.
LESTER E. SPRAY,
